MACHINE FOR BENDING PANELS

Filed March 15, 1929

9 Inventor:
C. B. Norris,
By Wm. F. Freudenreich,
Attorney.

UNITED STATES PATENT OFFICE

CHARLES B. NORRIS, OF GRAND RAPIDS, MICHIGAN, ASSIGNOR TO HASKELITE MANUFACTURING CORPORATION, A CORPORATION OF NEW YORK

MACHINE FOR BENDING PANELS

Application filed March 15, 1929. Serial No. 347,438.

The present invention relates particularly to the bending of plywood panels to produce from each two or more sides or portions of such sides of a boxlike structure; and it has 5 for its object to produce a simple and novel means for so bending panels.

The various features of novelty whereby my invention is characterized will hereinafter be pointed out with particularity in the 10 claims; but, for a full understanding of my invention and of its objects and advantages, reference may be had to the following detailed description taken in connection with the accompanying drawing, wherein:

15 Figure 1 is a perspective view of an apparatus embodying the present invention; Fig. 2 is a side view of the apparatus, on a smaller scale than Fig. 1, showing one of the clamping bars in position; Fig. 3 is an edge view 20 of a second clamping bar; and Fig. 4 is a perspective view of the bending implement.

25 Referring to the drawing, 1 represents a hollow block, conveniently of cast iron, having a contour corresponding to the inside of the box whose sides, or some of the sides of which, the panel is to form. The block therefore constitutes a form. Steam pipes 2 and 3 are connected to the bottom of the form so 30 that steam under a considerable pressure, say about ninety pounds to the square inch, may be introduced into the form.

35 The vertical corners of the block or form are rounded. On each side of the form is a swinging flap in the form of a heavy metal plate whose height is approximately equal to that of the form and whose width is considerably less than the corresponding dimension of the side of the form beside which the flap is located. These flaps are indicated at 40 4, 5, 6 and 7. Each flap is hinged at its lower end to the form by means of suitable hinges 8.

45 It will be seen that a panel may be bent around the form and be clamped against its four sides by means of the swinging plates or flaps. The flaps are held in their raised positions, closed on the work, in any suitable way, conveniently by means of clamping devices such as shown in Figs. 2 and 3. One 50 of these clamping devices comprises a spring bar 9 having the ends 10 bent laterally on the

same side. The parts are so proportioned that when the bar is placed above the form, extending in the lengthwise direction of the latter, the bent ends may be sprung down outside of the upper ends of the end flaps 5 and 7 as indicated in Fig. 2. The flaps 4 and 6 may be held in place by means of a similar clamp comprising a spring bar 11 having laterally bent ends 12, as shown in Fig. 3.

55 In order to facilitate the bending of the 60 panel about the form, I provide a simple bending device consisting of a fork having two parallel arms 14, 14 and a handle 15. At the free ends of the arms or prongs of the fork are hooks 16. Extending between the 65 arms or prongs, inwardly from the hooks, is a roller 17. The distance between the arms or prongs of the fork is slightly greater than the height of the form, so that one arm or prong may be slipped on top of the form and 70 the other underneath. Near each corner of the form, on top thereof, is an upwardly projecting pin 18. There are similar pins 19 on the bottom of the form, each of the latter pins being axially aligned with the corresponding 75 upper pin. The parts are so proportioned that when the bending device is slipped on the form at any corner, the hooks on the bending device will engage with one of the upper pins and the corresponding lower pin, so that 80 the bending device may be swung about such pins. The lower pins 19 may also serve the purpose of legs to support the form. In the arrangement shown, the pins 19 are secured 85 at their lower ends to a pair of supports 20 that may rest upon and be secured to a suitable bench or table.

85 In using the apparatus, the panel to be bent is placed between the form and the flap 4, for example, and the flap is locked in its holding 90 position by means of the clamp bar shown in Fig. 3. The bending device is then applied as shown in Fig. 1, with the panel lying between it and the form. The flap 7 being in a lowered idle position, the bending device is 95 swung forward toward the observer, bending the panel around the corner past which the bending device swings. The bending device is then applied at the corner on the opposite side of the flap 4, and a second bend is made 100

in the panel which now has been bent into a U-shape. The flaps 5 and 7 are now locked in their clamping positions, as shown in Fig. 2, and the free ends of the panel are then bent to lie flat against the side of the form on which the flap 6 is located. The flap 6 is then swung up and clamped in place, so that now the panel is being firmly held flat against the four sides of the form.

10 The panel should be damp in the zones where the bends are to occur, to facilitate the bending thereof. The heat of the form dries out the damp areas and causes the bends to set, so that when the dried panel is removed 15 from the form it will remain approximately in the shape into which it is bent. If it is not desired to leave the panel on the form until it has dried, it may be removed after the bending operation has been completed, and 20 be placed in a suitable holder until it has cooled and dried.

The entire panel should not be moistened, as that simply would make it necessary to drive out more moisture in the drying operation. I have found that a very simple way 25 of supplying the necessary moisture in only those areas where bends are to occur is to lay the panels on absorbent pads that rest in a body of water. These pads are long enough 30 to extend across the panel and are of such a width that the strip moistened thereby will not be needlessly wide. The pads are laid in the water, parallel with each other and at the proper distances between centers to cause 35 them to register with the lines on which bends are to be made when the panel is laid thereon.

While I have illustrated and described with particularity only a single preferred form of 40 my invention, I do not desire to be limited to the exact structural details thus illustrated and described; but intend to cover all forms and arrangements which come within the definitions of my invention constituting the appended claims.

45 I claim:—

1. A machine for bending panels comprising a form having rounded corners, projecting pins at the ends of the form at the axes about which the corners are curved, and a 50 bending device comprising a fork having at the free ends of its prongs hooks one of which is adapted to engage with any one of the pins at one end of the form while the other engages the corresponding pin at the other end.

55 2. A machine of the character described comprising a rectangular form, projecting pins at both ends of the form in the vicinity of the four corners, a flap hinged to the lower end of each side of the form and adapted to be swung up into a working position beside that side, means for securing the flaps in their raised positions, and a bending device comprising a fork having at the free ends of its 60 prongs hooks one of which is adapted to en-

gage with any one of the pins at one end of the form while the other engages a corresponding pin at the other end.

3. A machine for bending panels comprising a form, projecting pins at the ends of the form, the pins at one end being aligned with the corresponding pins at the other end, and a bending device comprising a fork having at the free ends of its prongs hooks one of which is adapted to engage with a pin at one end of the form while the other engages the corresponding pin at the other end.

In testimony whereof, I sign this specification.

CHARLES B. NORRIS.
